UNITED STATES PATENT OFFICE.

ROBERT J. BARKLEY, OF CHANUTE, KANSAS.

DESIGN FOR AN EGG-CARTON FILLER.

SPECIFICATION forming part of Design No. 29,512, dated October 18, 1898.

Application filed August 23, 1898. Serial No. 689,360. Term of patent 14 years.

To all whom it may concern:

Be it known that I, ROBERT J. BARKLEY, of Chanute, in the county of Neosho and State of Kansas, have invented and produced a new and original Design for an Egg-Carton Filler, of which the following is a full, clear, and exact description.

Reference is to be had to the accompanying drawings, forming a part of this specification, in which similar characters of reference indicate corresponding parts in both the figures.

Figure 1 is a plan view of an egg-carton filler illustrating my design, and Fig. 2 is a side view thereof.

The design in its entirety presents the appearance of an oblong rectangular figure made up of two rows of small squares and comprises the three longitudinal strips *a*, *b*, and *c*, ranging parallel with each other, and a series of parallel strips *d*, ranging transversely of the strips *a*, *b*, and *c*. The outer strips *a* and *c* cross the transverse strips *d* at their respective end portions, while the strip *b* crosses the strips *d* at the center. The extremities of the strips *d* project slightly be-

yond the strips *a* and *c*, as at *d'*. In side and end elevation the strips *a* and *c* and the end strips *d* present the appearance of panels, as is shown with reference to the strip *c* in Fig. 2. In side elevation these strips *a* and *c* (as 30 is shown with reference to the strip *c* in Fig. 2) present the appearance of slits *e*, ranging vertically therein and respectively alongside of the ends *d'* of the strips *d*.

The leading feature of the design consists 35 in the oblong filler, presenting the three longitudinal strips *a*, *b*, and *c*, crossed by the strips *d*, with the outer strips *a* and *c* at the end portions of the transverse strips *d*, the said strips *d* extending beyond the longitudinal strips, as at *d'*, and the projecting ends *d'* paralleling adjacent vertical slits *e*, appearing in the outer longitudinal strips *a* and *c*.

I claim—

The design for an egg-carton filler, herein 45 shown and described.

ROBERT J. BARKLEY.
